UNITED STATES PATENT OFFICE.

LOUIS JENSEN, OF CHICAGO, ILLINOIS, ASSIGNOR TO UNITED AUTOGRAPHIC REGISTER COMPANY, OF CHICAGO, ILLINOIS, A CORPORATION OF ILLINOIS.

PAPER-SUPPLY ATTACHMENT FOR TYPE-WRITERS.

1,243,942.

Specification of Letters Patent. Patented Oct. 23, 1917.

Application filed January 31, 1916. Serial No. 75,273.

To all whom it may concern:

Be it known that I, LOUIS JENSEN, a citizen of the United States, residing at Chicago, in the county of Cook and State of Illinois, have invented new and useful Improvements in Paper-Supply Attachments for Type-Writers, of which the following is a full, clear, and exact description.

My invention relates to improvements in attachments used in connection with type-writing machines for supplying a continuous web of paper to the platen carried by the reciprocable carriage, and particularly to the attachments for which Letters Patent of the United States were granted to E. J. Barker, May 25, 1915, No. 1,140,493, and which maintains a hanging slack portion of the continuous web.

In the attachments covered by said patent the motion of the platen was transmitted to the supply-rollers for maintaining the slack of paper fed thereto by mechanism that was carried by and added considerable weight to the carriage of the typewriter and was directly and permanently connected to transmission devices which included parts that had to be pulled along by and reciprocated synchronously with said carriage.

The principal object of my present invention is to materially reduce the comparatively great weight heretofore placed upon and carried by the carriage, and to absolutely remove the resistance to its movement by the above mentioned synchronously movable parts. It is a further object of my invention to provide means for adjusting the relative movements of the platen and said supply-rollers. These and other objects I accomplish by the means hereinafter fully described, and as particularly pointed out in the claims.

In the drawings:

Figure 1 is a plan view of a typewriting machine and its support to which my improvements are applied.

Fig. 2 is a rear elevation thereof with the lower portion of said support broken away.

Fig. 3 is a side elevation of said typewriting machine and a portion of its support with the ink ribbon-reels and mechanism for actuating the same eliminated.

Fig. 4 is a perspective view of the carriage shifting lever and mechanism actuated thereby for rotating the platen and transmitting motion to the supply-rollers, detached from the machine.

Fig. 5 is a transverse section of the platen removed from the machine, and taken on dotted line 5—5, Fig. 1.

Fig. 6 is a horizontal section of a portion of said machine, taken on dotted line 6, 6, Fig. 3, looking in the direction indicated by the arrows.

Fig. 7 is a vertical longitudinal section of a portion of said machine taken on dotted line 7—7, Fig. 2, and showing the supply-roller mechanism in side elevation.

Fig. 8 is a detail view showing mechanism for adjusting the throw of the devices for rotating the supply-rollers.

Fig. 9 is a detail view of a fragment of said improved machine.

Referring to the drawings, A represents the stationary supporting-frame of a typewriting machine of any suitable design, and B represents the transversely reciprocable carriage in the side-frames of which a platen C is journaled. The journal X of this platen at its right hand end extends through its bearings and has a ratchet c securely mounted thereon, and immediately next this ratchet c, it has an arm a pivotally mounted thereon which projects upward and forward slightly. This arm is provided with a downward extension b below its pivot, and the lower end edge of this extension terminates below the periphery of ratchet c, and is, preferably, made to describe a curve struck from the center of its pivot, or from a center slightly offset therefrom, substantially as shown in Fig. 5 of the drawings.

Immediately next this arm a a bell-crank d is pivoted, near one of its rounded angles, on the journal of the platen, and the lowermost angle of this bell-crank has a laterally projecting stud upon which a pawl e is loosely pivoted, the forward pointed end of which is kept pressing against the curved lower edge of extension b of arm a by a spring f one end of which is coiled around and fastened to the stud upon which the pawl is pivoted and the other end of which

extends to and bears upward against a pin *g*. The bell-crank constitutes the medium through which reciprocable motion is imparted to the pawl, and the throw of this reciprocal movement is such that the point of the pawl as it approaches the limit of its forward movement will ride beyond the curved edge of extension *b* and engage the teeth of pawl *e*, and by adjusting the rotatable movement of arm *a* said pawl will, during its forward movement, pass beyond the edge of the extension and engage the teeth of ratchet *c* and impart a greater or less degree of circular movement thereto and thus turn the platen to obtain the space between the lines of the typewritten matter desired.

The bell-crank has a link *D* connecting its rear uppermost angle to the end of a rocking-bar *E*, which is securely mounted at a suitable point between its ends upon the rear end of a superposed horizontal rock-shaft *F*, the axis of which is substantially at right angles to the axis of the platen. This rock-shaft, which is present in most typewriting machines, and is usually used at the end of the right hand reciprocal throw of the carriage to impart the necessary movement of the platen to advance the paper, and at the same time move the carriage back to the right hand throw of its reciprocation, is journaled in suitable bearing *G*, which latter may be of any desired construction and permanently secured to the side-frame of the carriage in some manner or other. The forward end of this rock-shaft extends beyond its bearings a suitable distance and is usually bent downward to form a hand-grasp for the operator, and is usually termed the "spacing-lever."

The end of rocking-bar *E* opposite link *D* is connected, through the medium of a link *H* to the adjacent forward extension 10 of one of the parallel end members 12 of a horizontal pressure-bar 13, which latter extends parallel to the platen at the rear of the carriage, and from end to end of the same, and has its parallel end members 12 extend forward and suitably secured to the ends of a rock-shaft 14 journaled in the ends of the side-frames of the carriage. When rock-shaft *F* is rocked, rocking-bar *E* thereon pushes extension 10 of the adjacent end member 12 upward through the medium of link *H*, and the pressure-bar 13 moves downward and engages an anti-friction roller 17 journaled on a stud projecting forward from the end of one branch of the rocking-beam 15.

Rocking-beam 15 is arranged in the direction of length of the pressure-bar, and it is fulcrumed mediate its ends to the upper end of a stationary standard 16 that is secured to and arises from the rear of supporting frame *A* of the machine. The branch of

this rocking-beam carrying the anti-friction roller 17 is kept normally pressing upward toward the pressure-bar 13 by means of a spring 18 that has one end permanently secured to standard 16 and its opposite end bearing upward against the underside of said branch of the rocking-beam. The end of the rocking-beam opposite roller 16 is connected by means of a depending connecting-rod 19 to the pivotal pin 21 of a pawl 20, and this pivotal pin 21 projects laterally from an arm 22, the opposite end of which is loosely mounted on the extended end of a journal 23 of a feed-roller 24, which latter has bearings in the ends of hangers 25 secured to and extending rearwardly from the ends of a rock-shaft 26 that is journaled in suitable bearings in the overhang 27 projecting rearwardly from the upper ends of parallel upright-members 28, 28, of the rack-frame, in the rearwardly and downwardly projecting brackets 29 of which the paper-rolls 30 are journaled from which the paper is supplied to the platen.

Shaft 26 extends parallel to the axis of feed-roller 24, and when pawl 20 is given an upward movement by connecting rod 19 the outer pointed end of said pawl engages a ratchet 31, which latter is securely mounted upon the adjacent extended end of the journal of roller 24, and moves said roller.

Roller 24 has its central portion slightly increased in diameter and knurled, and this knurled portion engages a superposed feed-roller 32, whose ends are journaled in brackets 33 that are secured to or made integral with the rear portion of overhang of uprights 28 of the rack-frame.

There are usually several rolls of paper 30 journaled in the rack-frame, and the webs thereof are run upward to and between feed-rollers 24 and 32, and in order to facilitate the separation of the lower roller 24 from the upper roller 32, when it is desired to thread the webs of paper from rolls 30 between them, I have provided a rock-shaft 34 which is parallel to rock-shaft 26 and is journaled in the overhangs 27 of the rack. One extended end of shaft 34 has a crank 35 secured thereto, and the opposite extended end of this shaft 34 is provided with a symmetrical pear-shaped cam 36, substantially as shown in Fig. 3 of the drawings. This cam engages the under upwardly inclined edge of a forward extension 37 of the adjacent hanger 25, and when the crank on the opposite end of shaft 34 is properly moved, cam 36 engages the under edge of said extension 37 and moves arm 25, shaft 34 and hangers downward and moves supply-roller 24, journaled therein, downward away from the upper feed-roller 32—said hangers 25 and roller 24 being normally pressed upward to hold said rollers in engagement by a coil-spring 38 surrounding

shaft 26 and having one end securely fastened to this shaft and its opposite end movably retained against shaft 34.

The end of the journal of roller 23 opposite ratchet 31 extends through its bearings and has a sprocket-wheel 39 securely mounted thereon, and this sprocket-wheel is connected by means of a forwardly extending chain 40 to near the front of the machine 10 where it engages a sprocket-wheel 41 journaled in a hanger 42 depending from the underside of the top 43 of the table upon which the stationary frame of the typewriting machine is mounted. These portions 40 and 41 and their associated parts afford a means whereby the paper may be manually caused to be unwound from their rolls to produce the required slack between them and the platen.

In order to regulate the throw of connecting-rod 19 and the movement of supply-roller 24 actuated thereby, I have provided means that engage the underside of the branch of rocking-beam 15 opposite that in which the anti-friction wheel 17 is journaled, and limit the downward movement thereof. These means comprise a segmental gage-plate 44, the lower end of which is pivoted to the standard 16 at a suitable point 25 below the fulcrum of the rocking-beam, substantially as shown in Fig. 8 of the drawings. The curvature of the upper end edge 45 of this plate is struck from a center whose radius is the same as the center of length thereof is from the pivotal pins of the gage-plate, but is eccentric to said pivotal axis, so that when the gage-plate is pushed forward the upper eccentric edge thereof will push against the under edge of said branch 30 of the rocking-beam and limit the downward movement thereof. At each end of this upper edge 45 there are upwardly projecting studs 46, 46, that limit the reciprocations of the gage-plate, and about midway its 35 length the rear edge thereof is provided with a segmental slot 47 which is struck from its pivotal axis, and a screw 49, tapped laterally through the standard, passes through this slot and has a thumb-nut 48 screwed 40 onto its end, which is manipulated to clamp the gage-plate and retain it in any position to which it may be adjusted. For convenience in manipulating this gage-plate, I have provided it with a lug 50 projecting rearwardly from its rear edge, but this may be 45 dispensed with, if desired.

What I claim as new is:

1. The combination in a typewriting machine with the reciprocable carriage, a platen journaled therein, means for rotating said platen, a roller having stationary bearings independent of the carriage upon which a roll of paper is mounted, mechanism movable with said carriage and actuated by said 60 means, and devices for rotating said roller 65

that are supported independently of said carriage and are depressed by said mechanism when said platen is rotated.

2. The combination in a typewriting machine with the reciprocable carriage, a platen journaled therein, means for rotating said platen, mechanism movable with said carriage and actuated by said means whereby a web of paper is fed from a roll to said platen, and devices for rotating said roll 70 which are supported independently of and normally disconnected from said carriage and depressed by said mechanism when said platen is rotated.

3. The combination in a typewriting machine with the reciprocable carriage, a platen journaled therein, means for rotating said platen, and a pressure-bar actuated by said means, whereby a web may be fed from a roll of paper journaled independently of 80 said carriage to said platen, and devices for rotating said roll which are supported independently of said carriage but normally disconnected therefrom and are actuated by said pressure-bar when said platen is ro- 85 90

4. The combination in a typewriting machine with the reciprocable carriage, a platen journaled therein, means for rotating said platen, and mechanism movable with said 95 carriage and actuated by said means, whereby a web of a roll of paper may be fed to said platen, and adjustable devices for rotating said roll which are supported independently of and normally disconnected 100 from said carriage and depressed by said mechanism when said platen is rotated.

5. The combination in mechanism of the kind specified with a reciprocable carriage, a platen journaled therein, means for rotat- 105 ing said platen, and a pressure-bar actuated by said means, whereby a web of a roll of paper journaled independently of said carriage may be fed to said platen, a rocking-beam one end of which is actuated by said 110 pressure-bar when said platen is rotated, and mechanism actuated by said rocking-beam for rotating said roll when the platen is ro- 115 tated.

6. The combination in mechanism of the 115 kind specified with a reciprocable carriage, a platen journaled therein, a pressure-bar extending horizontally back of and parallel to said carriage, and mechanism for simultaneously rotating said platen and depress- 120 ing said bar, whereby a web of a roll of paper journaled independently of said carriage may be fed to said platen, and devices depressed by said bar and adapted to rotate said roll simultaneously with said platen. 125

7. The combination in mechanism of the kind specified with a reciprocable carriage, a platen journaled therein, a pressure-bar extending horizontally back of and parallel to said carriage, and mechanism for simulta- 130

neously rotating said platen and depressing said bar, of means whereby a web of a roll of paper journaled independently of said carriage may be fed to said platen, and a rocking-beam depressed by said bar, and means actuated by and adapted to rotate said roll simultaneously with said platen.

8. The combination in mechanism of the kind specified with a reciprocable carriage, 10 a platen journaled therein, a pressure-bar extending horizontally back of and parallel to said carriage, and adjustable mechanism for simultaneously rotating said platen and depressing said bar, of means whereby a web 15 of a roll of paper journaled independently of said carriage may be fed to said platen, and devices depressed by said bar and adapted to rotate said roll simultaneously with said platen.

20 9. The combination in mechanism of the kind specified with a reciprocable carriage, a platen journaled therein, a pressure-bar extending horizontally back of and parallel to said carriage, and adjustable mechanism 25 for simultaneously rotating said platen and depressing said bar, of means whereby a web of a roll of paper journaled independently of said carriage may be fed to said platen, and adjustable devices depressed by 30 said bar and adapted to rotate said roll simultaneously with said platen.

10. The combination in mechanism of the kind specified with a reciprocable carriage, a platen journaled therein, a pressure-bar 35 extending horizontally back of and parallel to said carriage, and mechanism including a ratchet secured on the journal of said platen, an adjustable arm loosely mounted on said journal alongside said ratchet, and 40 a pawl engaging the lower eccentrically curved edge of an extension of said arm as it advances to engage said ratchet for simultaneously rotating said platen and depressing said bar, and devices depressed by said 45 bar and adapted to simultaneously feed a sheet of paper to said platen.

11. The combination in a machine of the kind specified with a reciprocable carriage, a platen journaled therein, means for rotating said platen, and a pressure-bar which is depressed when said platen is rotated, of a rocking-beam one branch of which is adapted to be engaged by said pressure-bar, adjustable means for limiting the rocking 55 movement of said beam, a pair of feed-rollers between which a web of paper passes in transit to the platen, and devices actuated by said rocking-beam for rotating said rollers.

60 12. The combination in a machine of the kind specified with a reciprocable carriage, a platen journaled therein, means for rotating said platen, and a pressure-bar which is depressed when said platen is rotated, of a 65 rocking-beam one branch of which is

adapted to be engaged by said pressure-bar, a pair of feed-rollers between which a web of paper passes in transit to the platen, and devices actuated by said rocking-beam for rotating said rollers. 70

13. The combination in a machine of the kind specified with a reciprocable carriage, a platen journaled therein, means for rotating said platen, and a pressure-bar which is depressed when said platen is rotated, of a rocking-beam which is adapted to be engaged by said pressure-bar when said platen is rotated, a pair of feed-rollers journaled independently of said carriage one of which is adapted to be moved out of engagement 80 with the other, means whereby a web of a roll of paper journaled independently of said platen may extend between said rollers and from thence to said platen, and devices for imparting motion from said rocking-beam to said rollers. 85

14. The combination in a machine of the kind specified with a reciprocable carriage, a platen journaled therein, means for rotating said platen, and a pressure-bar which is depressed when said platen is rotated, of a rocking-beam which is adapted to be engaged by said pressure-bar when said platen is rotated, a pair of feed-rollers journaled independently of said carriage, a ratchet on 90 the journal of one of said rollers, a pawl engaging the same, a connecting-rod for transmitting the motion of said rocking-beam to said pawl, means whereby a web of a roll of paper journaled independently of 95 said platen may extend between said rollers and from thence to said platen.

15. The combination in a machine of the kind specified with a reciprocable carriage, a platen journaled therein, means for rotating said platen, and a pressure-bar which is depressed when said platen is rotated, of a rocking-beam which is adapted to be engaged by said pressure-bar when said platen is rotated, a pair of feed-rollers journaled 105 independently of said carriage, simultaneously movable hangers in which the lower roller has bearings, a ratchet on the journal of said last-mentioned roller, an arm loosely mounted thereon, a pawl pivoted to said 110 arm and engaging said ratchet, a connecting-rod connecting said rocking-beam and pawl, means whereby a web of a roll of paper journaled independently of said carriage may extend between said rollers and 115 from thence to said platen.

16. The combination in a machine of the kind specified with a reciprocable carriage, a platen journaled therein, means for rotating said platen, and a pressure-bar which is 125 depressed when said platen is rotated, of a rocking-beam which is adapted to be engaged by said pressure-bar when said platen is rotated, adjustable means for limiting the rocking movement of said beam, a pair of 130

feed-rollers journaled independently of said carriage, simultaneously movable hangers in which the lower roller has bearings, a ratchet on the journal of said last-mentioned roller, 5 an arm loosely mounted thereon, a pawl pivoted to said arm and engaging said ratchet, a connecting-bar connecting said rocking-beam and pawl, means whereby a web of a roll of paper journaled independ-

ently of said carriage may extend between 10 said rollers and from thence to said platen.

In witness whereof I have hereunto set my hand this 20 day of January, 1916.

LOUIS JENSEN.

Witnesses:
